E. J. FRANCKE

HAIR CURLER

Filed April 18, 1922.

Fig. 2.

Edward J. Francke Inventor

By Philip L. Full
Attorney

UNITED STATES PATENT OFFICE.

EDWARD J. FRANCKE, OF OMAHA, NEBRASKA.

HAIR CURLER.

Application filed April 13, 1922. Serial No. 554,437.

To all whom it may concern:

Be it known that EDWARD J. FRANCKE, citizen of the United States, residing at Omaha, in the county of Douglas and State 5 of Nebraska, has invented certain new and useful Improvements in Hair Curlers, of which the following is a specification, reference being had therein to the accompanying drawings.

10 The invention relates to hair curlers and has for its object to provide a hair curler wherein a tubular member is pivotally connected on a transverse portion of a U-shaped frame and adapted to be folded downwardly 15 between the arms of the U-shaped frame for bending hair previously wound around the tubular member. Also to provide the arms of the U-shaped member with a slidible disc having an aperture therein for the reception 20 of the free end of the tubular member and forming means whereby the tubular member may be held in clamped position and the hair forced into close engagement.

A further object is to provide an elongated tapered rod adapted to be heated and inserted into the tubular member for heating the tubular member and consequently causing the hair to curl. The taper of the heating rod allowing the rod to be easily 25 inserted in the tubular member and at the same time allowing the outer end of the tapered rod to jam against the inner wall of the tube and prevent easy displacement of the heating rod.

30 A further object is to provide the ends of the arms of the U-shaped member with flattened portions which prevent the discs from coming off the arms and also cooperate with diametrically disposed slots in the handle of the rod for additionally preventing displacement thereof.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit 50 of the invention.

In the drawings:-

Figure 1 is a perspective view of the device showing the tubular member ready to be moved downwardly for clamping the hair and the heating rod in position to pass

through the disc and into the tubular member.

Figure 2 is a top plan view of the device, part of the handle being broken away.

Referring to the drawings, the numeral 1 designates a tubular member, around which the hair 2 of the operator is wound. Pivotally mounted at 3 on the transverse portion 4 of the U-shaped member 1 is the tubular member 5, which member 5 when moved downwardly passes between the arms 6 of the U-shaped member 1, thereby in connection with said arms forming compound bends in the hair, which will give a wavy effect. After the tubular member 5 has been moved downwardly the disc 7 is moved inwardly on the arms 6 which pass through apertures 8 of the disc 7. When the disc 7 is moved inwardly the free end 9 of the tubular member 5 passes through the aperture 10 of the disc 7, thereby holding the tubular member in clamped position and at the same time crowding the hair 2 in the direction of the transversely disposed portion 4 of the U-shaped member 1 for insuring a uniform curling operation. After the disc 7 has been moved as above set forth, the heating rod 11 which has been previously heated is passed into the end 12 of the tubular member and the heat radiated therefrom soon heats the tubular member 5 and consequently the hair is curled, not only by the clamping action but by the heat. The rod 11 is preferably tapered as shown so that

its small end 13 may easily enter the tubular member 12 and its large end 14 will jam in the end 12 of the tubular member thereby preventing easy displacement of the heating rod. However to additionally insure the holding of the heating rod 11, the handle 15 thereof is provided with diametrically disposed inclined slot 16, with which the flattened ends 17 of the arms 6 cooperate when the handle 15 is forced inwardly for holding the heating rod against outward displacement.

From the above it will be seen that a curling iron is provided wherein the clamping of the hair is positive, the burning of the hair obviated and the hair being clamped before the heating rod 11 is inserted obviates the burning of the hands of the operator and at the same time the relatively cold tubular member 5 will prevent excess radiation of heat which would burn the hair.

The invention having been set forth what is claimed as new and useful is:—

1. A hair curler comprising a U-shaped frame having oppositely disposed arms, a pivoted tubular member pivoted between said arms, a slidable apertured disc mounted on the arms and adapted to receive the free end of the tubular member, a heating rod removably disposed within the tubular member, members carried by the ends of the arms of the frame and cooperating with oppositely disposed recesses in a handle carried by the heating rod whereby said rod is prevented from outward movement.
- 15 2. A hair curler comprising a U-shaped frame, a pivoted tubular member pivoted to the transverse portion of the frame, a

slidable apertured disc mounted on the arms of the frame and adapted to receive the free end of the tubular member, a tapered heating rod disposed in said tubular member and frictionally held against displacement, flattened portions carried by the arms for preventing the disc from coming off the arms, a handle member carried by the heating rod, said flattened portions of the arms cooperating with diametrically disposed slots in the handle member for additionally holding the heating rod against outward displacement.

In testimony whereof I hereunto affix my signature.

EDWARD J. FRANCKE.
